UNITED STATES PATENT OFFICE.

ELEUTHERE PAUL DU PONT, OF MONTCHANIN, DELAWARE.

SHIP CONSTRUCTION.

Application filed October 16, 1922. Serial No. 594,707.

To all whom it may concern:

Be it known that I, ELEUTHERE PAUL DU PONT, a citizen of the United States, residing at Montchanin, county of New Castle, 5 and State of Delaware, have invented a new and useful Improvement in Ship Constructors, of which the following is a full, clear, and exact description, reference being had to the accompanying drawings, which form 10 a part of this specification.

This invention relates to an improvement in hull construction and propeller shaft connections for auxiliary sailing vessels arranged to draw the propeller within the 15 plane of the hull when the vessel is to be driven by its sails alone.

The object of my invention is to provide a construction which is so arranged that when the vessel is driven by propeller, the 20 portion of the propeller shaft, its rear or strut bearing and the lines of the hull will have the appearance of a vessel having a shaft and propeller mounted in fixed relation to the hull, and which is also so arranged that the entire shaft, its supports and 25 the propeller can be shifted to a position within the lines of the hull without changing the contour of the hull when the propeller and its shaft are in either position.

This is accomplished by providing the portion of the hull over the portion of the shaft which protrudes from the hull when the propeller is used for driving, with a 30 movable section, having two faces whose contour is such that when either face is positioned to form a portion of the hull surface the contour or lines of the hull will be unbroken.

The protruding portion of the propeller 40 shaft and the outer shaft bearing are so mounted on the movable section that when the section is in one position, one face of the section forms a portion of the hull surface, and when the section is in another position the other face of the section forms a portion of the hull surface, while the shaft and its bearings, as well as the propeller, are within the planes of the hull.

The precise nature of my invention will 50 best be understood by reference to the accompanying drawings, which will now be described, it being promised, however, that various changes may be made in the details of construction and arrangement without departing from the spirit and scope of my 55 invention as defined in the appended claims.

Fig. 1 is a side elevation of the hull of vessel equipped with one form of my invention.

Fig. 2 is a transverse section on the line 60 2-2 of Fig. 3.

Fig. 3 is a sectional view on the line 3-3 of Fig. 2 of a portion of the hull.

Fig. 4 is a view, similar to Fig. 3, with the propeller and its shaft within the hull. 65

Fig. 5 is a detail sectional view of the locking means shown in Fig. 2.

In the drawings, the reference character *a* designates the hull of the vessel, which may be formed of any suitable material. In the 70 form shown in the drawings, the major portion is constructed of wood.

Mounted in suitable bearings is a main shaft *b*, and connected to the main shaft by a universal coupling *c* is the propeller shaft 75 *d* having a propeller *e* connected to the outer end thereof. The hull *a* is provided with a movable section between the stern post thereof and the coupling *c*, or at that portion of the hull under which the protruding portion of the propeller shaft extends and slightly forward thereof.

The movable section is built up of a rear cast frame member *f* having arms extending therefrom carrying at their outer ends a 85 bearing *g* for the outer end of shaft *d*. The front end of this movable section is provided with a casting *h* which forms the bearing for the other end of shaft *d*. Connected to the frame members *f* and *h* and a second end-forming member *i* are plates *j* and *k*. These plates *j* and *k* are shaped to conform to the lines of the hull and form continuations of the surface of the hull when properly positioned relative thereto. 95

Surrounding the opening in the hull for the movable section at both ends is a metal frame *m* which is provided with bearings for trunnions *n* and *o* on the frame *f* and *h*, respectively. The shaft *d* extends through the trunnion *o* and at an angle to the axis of trunnions *n* and *o*. *p* is a stuffing box for the shaft *d* in the trunnion *o*, and *q* is a stuffing box for the trunnion *o*. Connected to the frame *m* is a water-tight sheet 100 metal covering *s*, which is semi-circular in cross-section and which is concentric with the axis *x* of trunnions *n* and *o*. Rotatably mounted in a bearing in frame *m* is a vertical shaft *t* having an operation handle *u* at one end and a locking cam *v* at the other end. The cam *v* is arranged to engage 110

grooves in frame *f* to lock the movable hull section in either of its positions.

w is a handle connected to the outer end of trunnion *o* for reversing the position of 5 the movable hull section.

When the vessel is driven by means of the propeller, the parts are in the positions shown in Figs. 1, 2 and 3, and in which the plate *k* forms a portion of the surface of 10 the hull, and as the surface of the plate and frames *f* and *h* conform to the lines of the hull and fill the opening in the hull, the hull surface will be unbroken. When the vessel 15 is under sail and the propeller shaft is not motor driven, the propeller and its shaft are drawn into the planes of the hull to cut down the resistance of passage of the vessel through the water, and is so shown in Fig. 4. 20 The propeller is drawn into the planes of the hull as follows: The shaft is rocked by the handle *u* to withdraw locking cam *v* from the slot in frame *f*, handle *w* is then rocked to shift the movable section of the hull 180° about the axis of trunnions *n* and *o*, as shown 25 in Fig. 4, and the movable section of the hull is then locked in its shifted position. When the parts are in the position shown in Fig. 4, the entire length of the propeller shaft, the 30 bearings therefor, and the propeller are within the planes of the hull, and as the outer surfaces of plate *j* and frame members *f* and *h* conform to the lines of the hull, the surface of the hull will be clear of obstructions. 35

The advantages of my invention result from the provision of means for supporting a portion of propeller shaft on a movable section of the hull of a vessel, said movable 40 section having two portions conforming to the lines or contour of the hull, and which section is so mounted on the hull that when the section is in one position the contour of the hull will be unbroken and partially 45 formed by one portion of the said section, while the propeller will be in driving position, and when shifted to another position the propeller will be drawn within the planes of the hull and the contour of the 50 hull will be completed by the other portion of said section, whereby I am enabled to provide a properly positioned and mounted propeller for the vessel which can be withdrawn into the hull and at the same time 55 provide a hull having the same contour regardless of whether the propeller is in driving position or within the hull.

Having now fully described my invention, what I claim and desire to protect by Letters 60 Patent is:

1. The combination of a vessel hull and a propeller thereon, said hull having a moveable section with two faces shaped to conform to the contour of the hull, means to 65 secure the section to align either face with

the hull, means to mount the propeller shaft on the section as to place the propeller in driving position when one face of the section is aligned with the hull and to position the propeller and shaft within the hull when the other face is aligned with the hull, a driving 70 shaft for the propeller shaft, and a flexible connection between the shafts.

2. A boat having a hull with a reversible section with two faces shaped to conform to 75 the lines of the hull, a propeller shaft, a propeller on said shaft, bearings for supporting said shaft so as to place the propeller in driving position when one of said faces is aligned with the hull and to position 80 the propeller and the shaft within the hull when the other face is aligned with the hull, and means to secure the section to the hull when either face is aligned with the hull.

3. A boat having a hull with an opening 85 in the bottom thereof, a closure for said opening, pivotal connections between the closure and the hull arranged to permit the closure to be swung about an axis extending in a longitudinal direction relative to the 90 hull, opposite faces of the closure being shaped to conform to the lines of the hull, means to lock the closure in two positions so that when the closure is locked in either 95 position the contour of the hull will be unbroken, a sectional propeller shaft, one section being mounted on the hull, the other being mounted on the closure, a flexible connection between the shaft sections, the one 100 section of the shaft extending from the hull into the space between the two faces of the closure and through one face thereof, and a propeller on the outer end of the last mentioned section of the shaft.

4. A boat having a hull with an opening 105 in the bottom thereof, a closure for said opening, pivotal connections between the closure and the hull arranged to permit the closure to be swung about an axis extending in a longitudinal direction relative to the 110 hull, opposite faces of the closure being shaped to conform to the lines of the hull, means to lock the closure in two positions so that when the closure is locked in either 115 position the contour of the hull will be unbroken, a sectional propeller shaft, one section being mounted on the hull, the other being mounted on the closure, a flexible connection between the shaft sections, the one 120 section of the shaft extending from the hull into the space between the two faces of the closure and through one face thereof, a propeller on the outer end of the last mentioned section of the shaft, and a water-tight hood 125 within the hull over the opening in the hull.

5. In a boat with a propeller arranged to be drawn within the lines of the hull and to be positioned in driving position on the exterior of the hull, comprising a hull with a 130 longitudinally extending opening in the

bottom thereof, a closure for said opening having two counter-part faces shaped to conform to the lines of the hull, and so arranged that when either face is in aligned position with the outerface of the hull the contour of the hull will be unbroken, a trunnion at each end of the closure, bearings for the trunnions on the hull, the trunnions and bearings being arranged to permit the closure to swing about an axis extending longitudinally of the hull, a sectional propeller shaft extending longitudinally of the hull, a universal joint between the two sections of the shaft, one of

said sections being rotatably mounted on the hull, the other section extending through one of the trunnions and one face of the closure, a stuffing box between the last mentioned trunnion and its bearing, a stuffing box for the shaft and the trunnion, a strut bearing for the outer end of the shaft connected to the closure, and a propeller on the end of the shaft.

In testimony of which invention, I have hereunto set my hand, at Wilmington, Delaware, on this 13th day of October, 1922.

ELEUTHERE PAUL DU PONT.
